UNITED STATES PATENT OFFICE.

NOAH W. KUMLER, OF DAYTON, OHIO.

IMPROVED METHOD OF PREVENTING SEALING-WAX FROM ADHERING TO MOLDS.

Specification forming part of Letters Patent No. **56,576**, dated July 24, 1866.

To all whom it may concern:

Be it known that I, NOAH W. KUMLER, of the city of Dayton, county of Montgomery, and State of Ohio, have discovered a new and useful Process for Preparing Metal Molds in which Sealing-Wax is Cast, which prevents the adhesion of the wax to the surface of the molds and enables me to remove the wax with facility and without injury.

This I accomplish by the application of quicksilver to the surface of the molds. To facilitate and accomplish this, I apply the quicksilver with chalk by friction or by first washing the surface of the molds with a solution of cyanide of silver or muriate of tin.

I do not claim the discovery of a new chemical principle; but I do claim the right to use and employ known material and principles for a new and useful purpose, when such application has never been used or known before.

What I therefore claim, and desire to secure by Letters Patent, is—

The application of quicksilver in the manner and for the purposes herein respectively set forth.

NOAH W. KUMLER.
